UNITED STATES PATENT OFFICE.

LEWIS HALLOCK NASH, OF SOUTH NORWALK, CONNECTICUT.

SPEED-REGULATOR.

SPECIFICATION forming part of Letters Patent No. 664,026, dated December 18, 1900.

Application filed March 6, 1899. Serial No. 708,006. (No model.)

To all whom it may concern:

Be it known that I, LEWIS HALLOCK NASH, a citizen of the United States, and a resident of South Norwalk, in the county of Fairfield and 5 State of Connecticut, have invented certain new and useful Improvements in Speed-Regulators, of which the following is a specification.

My present invention relates to speed-regulators; and it consists of certain novel parts 10 and combinations of parts, particularly pointed out in the concluding claims.

In the accompanying drawings I have shown 15 my invention applied in the form which is at present preferred by me; but it will be understood that various modifications and changes may be made without departing from the spirit of my invention and without exceeding the scope of the concluding claims.

Referring to the drawings, Figure 1 is a 20 side view of a speed-regulator involving my invention; and Fig. 2 is a cross-section on the line 2 2, Fig. 1. Fig. 3 shows in sectional detail the relation of the pivots of the shoe and of its pivoted support.

25 The following is a description of the structure shown in the drawings, illustrating the embodiment of my invention at present preferred.

3 is the engine-shaft, and 4 the driving- 30 wheel.

5 is the shaft of the driven mechanism, which in this case we will assume to be a dynamo.

6 is the driven wheel.

35 7 7 are friction-shoes (preferably faced with leather) by means of which the energy of the shaft 3 is communicated to the shaft 5.

8 8 are levers supported on pivots 9 9, carried by driven wheel 6, to which lever- 40 arms the shoes 7 7 are pivoted.

10 10 10 are the weighted ends of the arms 8 8.

11 11 11 are springs at one end attached to the spokes of the driven wheel 6 by adjustable nuts and at the other end attached to the arms 8.

The operation of the device is as follows: The speed of the wheel 4, driven by the engine, is more or less variable, and the object 50 is to maintain the speed of the driven wheel 6 more nearly invariable. The coiled springs 11 constantly tend to press the shoes 7, carried on the driven wheel, against the inner rim of the driving-wheel. By these friction-shoes the power is transmitted from one wheel

to the other. When, however, the driven wheel exceeds the normal predetermined speed, the centrifugal force of the weights 10 (or the lever ends without weights) overcomes the elasticity of the springs and withdraws 60 the shoes from contact with the driven wheel or diminishes such friction-contact, permitting the driving-wheel to exceed the speed of the driven wheel. In this construction the energy of the springs and the levers controlled 65 by centrifugal force constantly oppose each other. While the energy of the spring is substantially constant, the centrifugal force varies with the speed, and the shoes are controlled by the difference between the two. As 70 the wheels revolve in the direction of the arrow 12 all tendency to jam is avoided, since friction tends to release the shoe and not to clamp it.

Having thus described the structure which 75 in the form at present shown embodies my invention, what I claim, and desire to secure by Letters Patent, is—

1. In a speed-regulator, the combination of 80 rotative driving and driven members adapted to be connected to rotate in unison respectively with the motor and the mechanism being driven, levers pivoted upon said driven member, shoes carried by said levers and adapted to frictionally engage the driving 85 member, and springs connected with said levers and proportioned to neutralize the centrifugal force developed in said levers at the desired speed, and to swing the levers in opposition to the centrifugal force and so as to 90 apply the shoes at lower speeds and in the opposite direction to free the shoes at higher speeds.

2. In a speed-regulator the combination 95 with a driving and a driven wheel, mounted upon coincident axes, the driving-wheel having a friction-surface thereon, of levers pivoted near one end to the driven wheel, shoes carried on the short arms of the levers and adapted to engage the friction-surface upon 100 the driving-wheel, the short arms of the levers extending with the direction of slip of the driving-wheel upon the shoe, and springs acting in opposition to centrifugal force upon said levers.

LEWIS HALLOCK NASH.
